GEORGE KREMER, OF NEW YORK, N. Y., ASSIGNOR OF ONE-HALF TO ERNEST UNGER,
OF NEW YORK, N. Y.

PROCESS FOR PERMANENTLY WAVING HAIR.

1,164,102.

Specification of Letters Patent. Patented Dec. 14, 1915.

Application filed October 15, 1914. Serial No. 366,842.

To all whom it may concern:

Be it known that I, GEORGE KREMER, a subject of Austria, residing in the city, county, and State of New York, have invented certain new and useful Improvements in the Process for Permanently Waving Hair, of which the following is a specification.

My invention relates to an improvement 10 in the process of permanently waving the natural hair on a person's head.

It has been known to coil an entire strand of hair about a metal rod, to wrap this strand helically with a wet flannel so as to 15 completely cover the hair, to insert this wrapped hair into a closed tube containing a lotion, and finally to subject the entire length of the same to the action of the heat from an electric heating iron. While this 20 process gives some degree of satisfaction under certain conditions as when used for the first time on coarse thick hair, it possesses numerous disadvantages under other conditions. For instance, when used on fine hair, 25 it frizzles and discolors the ends, and when attempts were made to increase the thickness of these ends, by gathering more hair into the wrapped strands to give the necessary body, the coils were found to be too 30 thick at the base to permit the even and close waving effect desired. Another disadvantage is that after the hair has been once waved, and the process repeated to 35 wave the newly grown straight portion of the hair, an appreciable amount of the previous waved hair would break off, and as a result, this process has fallen into disfavor.

The primary object of my invention is to 40 wave permanently the newly grown straight hair without injuriously affecting the previously waved hair, and another object is to give an effective waved appearance to a head of fine fluffy hair without injuring the same.

This process consists in separating the 45 hair into strands, the greater the number of strands under usual conditions the better, and wrapping the base portion of each strand adjacent the person's head with a slightly twisted motion into a tightly wound 50 spiral on a curling rod of relatively small diameter. Each coil is wrapped closely in contact with the preceding coil so that the coils lose their circular cross sectional form 55 and are somewhat flattened on adjacent sides. The outer end portion of each strand,

in the case of fine hair, or the previously waved portion, in the case of hair which has been treated by a similar process, is allowed to fall free and loose, or it may be wound or braided about the outer end of the curler, 60 so as to gather the same out of the way of the operator. The coiled portion is then treated with a supersaturated saline solution, preferably in the form of a paste, a mixture composed of three parts sodium 65 hyposulfite, forty-eight parts sodium tetraborate, and seventeen parts of water, has been found to be quite effective. The saturated coiled portion is inclosed in a suitable wrapping and subjected to a steaming 70 action by encircling the coiled portion with some suitable heating means. Care must be taken so that the heat is confined to the base or unwaved portion of the strand as heat applied to the fine ends or to a previously 75 waved portion will kill the hair and cause it to break. Care must also be taken that the heat is not suddenly applied, it having been found best to cause the heat to gradually rise from room temperature to 80 about 800° F., for about twenty minutes, to shut off the heat for about four minutes, to give it a final heating for about four minutes, and then to allow it to cool while confined for about fifteen minutes. The entire 85 mass of hair is then washed clean of the saline solution, is dried by any suitable means and is then combed from the head outward across the juncture of the old and newly waved hair. This final combing has 90 the effect of bringing the old and new waves into continuity and presenting a uniform series of waves from the head outward toward the end. In the case of fine hair, it is best to leave the ends unwaved, but this 95 will not be noticed after the hair is dressed, as these end portions are usually drawn into a knot at the back of the head.

By means of the process as thus outlined, I am enabled to wave any character of hair, 100 and to wave the new growth without the disadvantages inherent in the previously known process.

In the accompanying drawing, the figure 105 shows a female bust with a head of hair partially waved and showing certain steps of the process.

The hair is shown separated into strands A wrapped about a curling tube B, which wrapped portion is confined in a flannel 110

wrapping C, which either entirely incloses the strand of hair or from which the end of the strand is allowed to fall loose as shown at D. The wrapped strand is en 5 circled adjacent its base by means of an electric heating device of any preferred form, such as is shown in U. S. patent to Groser and Unger, No. 1,103,506, July 14, 1914.

Having thus described my invention, I 10 claim:

1. In the art of permanent hair waving, the process for waving the newly grown hair on a head of hair which has been previously waved without damaging the previously 15 treated old hair, which process consists in separating the hair into strands, arranging the newly grown straight hair of each strand adjacent the person's head into a tightly wound spiral while permitting the previously 20 waved hair to remain in a position so as not to be affected by any heating action, confining said spiral portion, saturating the same with a saline solution, subjecting said confined saturated portion to the 25 action of heat gradually ranging from room temperature to a maximum temperature to give the hair a steaming treatment, said heat being directed thereto so as not to affect the previously waved portion, permitting said 30 heated portion to remain confined in its spiral form for a short period of time after the application of heat thereto has been discontinued, washing the hair to remove any saline solution present, and finally combing 35 both the previously waved and the newly waved portions across the juncture of these portions.
2. In the art of permanent hair waving, the process for waving the newly grown hair 40 on a head of hair which has been previously waved without damaging the previously treated old hair, which process consists in

separating hair into strands, arranging the newly grown hair of each strand adjacent the person's head into a tightly wound spiral 45 while permitting the previously waved hair to remain in a position so that it will not be affected by any heating action, confining said spiral portion, wetting the confined portion, subjecting said wetted portion to the 50 action of heat gradually ranging from room temperature to a maximum temperature to give the hair a steaming treatment, said heat being directed thereto so as not to affect the previously waved portion, permitting said 55 heated portion to remain confined in its spiral form for a short period of time after the application of heat thereto has been discontinued, finally combing both the previously waved and the newly waved portion 60 across the juncture of these portions.

3. The method of permanently waving the newly grown hair on a head of hair which has been previously waved without damaging the previously waved hair, which consists in separating the hair into strands, coiling the newly grown hair of one of the strands into a spiral and confining the coiled part while permitting the previously waved portion of said strand to fall free or to be 70 gathered into a position so that it will not be affected by the succeeding heat step, and subjecting this coiled portion to an intense heat for a limited period of time while insulating the previously waved portion from 75 the heating action.

Signed at New York in the county of New York and State of New York this third day of October A. D. 1914.

GEORGE KREMER.
